UNITED STATES PATENT OFFICE.

CALLIE S. CAMPBELL, OF NEW LONDON, OHIO.

MOLD.

1,271,849.

Specification of Letters Patent.

Patented July 9, 1918.

Application filed May 2, 1916. Serial No. 94,933.

To all whom it may concern:

Be it known that I, CALLIE S. CAMPBELL, a citizen of the United States, residing at New London, in the county of Huron and State of Ohio, have invented certain new and useful Improvements in Molds, of which the following is a specification.

This invention has relation to certain new and useful improvements in molds of that type that are especially designed to be used in casting iron or other metallic piping; and as its principal object, it contemplates the provision of cooling means therefor, such as will expedite the casting of the pipe or other structure being formed.

A further object of my invention is to provide a device of the type in question that is extremely simple in construction, strong and durable and highly practical from both the standpoint of the manufacturer and the standpoint of the user; and which, it is believed, may be manufactured at a comparatively low cost.

These objects are accomplished by such means as are shown in their preferred form in the accompanying drawings, described in the following specification and then more specifically pointed out in the appended claim.

30 In the accompanying drawings wherein like characters designate like parts throughout the several views:—

Figure 1 is a view in end elevation showing my invention as in its preferred embodiment;

Fig. 2 is a view in cross section showing more clearly the method of mounting the movable mold sections upon the base of the device;

40 Fig. 3 is a view in longitudinal section, showing means to control the ingress of molten metal, and means for conducting a cooling medium from the base to the interior of the movable mold sections;

45 Fig. 4 is a view in top plan of the base showing the stationary mold section thereon; and

Fig. 5 is a view in bottom plan of the movable mold section, showing the same as 50 in its preferred embodiment.

In reducing my invention to practice, I first provide a base 10 that may be constructed of any desirable material, the same carrying a detachable bottom plate 11 and 55 being hollow throughout the greater portion of its extent to form a compartment 12. The upper wall 13 of the base is provided

with a longitudinally arranged mold section 14 of the concavo-convex type which is to be of suitable configuration, in accordance 60 with the type of pipe section to be molded, and which forms an adjacent cavity 15 communicating with the compartment 12 of the base.

Upon the plate 13 of the base and preferably about the longitudinal edges thereof, I arrange spaced eye bearings 16 and 17 respectively, the alined bearings 16 being designed to receive a carrying rod or pintle 18 (see Fig. 2), while the bearings 17 are 70 employed to cooperate with suitable latch mechanism to be arranged on the movable mold member.

A body 19 is arranged to be movable with respect to the base 10, such as clearly 75 shown in Figs. 1 and 2, the same being constructed of any desirable material, and having spaced bearings 20 on one side thereof to be engaged with the pintle 18 whereby it may be held in pivotal relation. The 80 lower wall 21 of the member 19 is provided with a concavo-convex mold section 22 that is designed to lie in spaced relation to the mold section 14 when in a final position and which may have its under face formed of any desired configuration in consistence 85 with the type of pipe being cast. In the present embodiment, I have shown the under face of the mold section 22 provided with a series of cross zig-zag grooves or 90 cut out 23, whereby like offsets will be formed on the respective pipe sections, as is obvious. The under face of the bottom plate 21 of the member 19 is further cut away at certain points as shown at 24 and 95 further provided with receiving openings 25 for reception of studs 26 on the top plate 13 of the base member whereby apertured flanges will be formed on the respective pipe section that is being cast. However, this 100 construction is believed to be old in the art and it is to be understood that I do not claim the same in connection with my present invention.

The member 19 is further provided with 105 spaced portions 27 that are in turn provided with adjacent ways 28 and 29 respectively, for communication with the upper face thereof and the under face of the mold section 22. In the present embodiment, the ways 28 are designed to receive the molten metal prior to its passing into the cavity between the respective mold sections 14 and 22, while the ways 29 receive operating

levers 30 that are pivotally mounted in position, as shown at 31. Upon its under face the mold section 22 is cut away at certain points to provide orifices 32 for the reception of movable gate valves 33, the gate valves being in turn pivotally connected with the lower end of the operating levers 30 as at 34. It is contemplated to construct the valves 33 in a manner whereby they may 10 be moved into what will be hereinafter termed the inoperative position so as to permit the free ingress of material through the ways 28, as shown to the left in Fig. 3, or moved into a closed position as shown to 15 the right of Fig. 3 to prevent further entrance of material, but at the same time completely close the lower end of the way 29. In other words, the valves are arranged so that they will close the lower end of the 20 ways 29 at all times, thus preventing entrance of foreign material into the body of the mold. It may also be advisable to cut away one wall of the ways 29, as at 35 whereby a greater amplitude movement may be 25 imparted to the levers 30.

During the formation of the member 19, in the above stated manner, a longitudinally extending cavity or compartment 36 is formed therein which extends about the upper face of the mold section 22, about the portions 23 and beyond the ends of the respective mold section, as clearly shown in Fig. 2.

A flexible tube 37 may now be arranged to 35 establish communication between the compartment 12 of the base member and the compartment 36 of the member 19, such as shown in Fig. 3, the same having its ends passed through suitable apertures 38 in the 40 members, while an inlet pipe 39 may be connected with the base member to supply the cooling medium to the compartment 12 and a pipe 40 associated with the member 19 whereby the water or other cooling medium 45 may find egress from the compartment 36.

In other words, as soon as the member 19 is moved into its final position upon the base 10 such as shown in Fig. 2, the latch members 41 thereof may be engaged with 50 the bearings 17 of the base member, whereby it will be held in a secure position. Water or other cooling medium may then be introduced into the compartment 12 and the cavity 15 of the base member by way of 55 the pipe 39, after which it will travel through the pipe 37 to the cavity or compartment 36 of the member 19 and circulate about the upper wall of the mold section 22.

From the compartment 36, the water or 60 other cooling medium will pass outwardly

through the outlet pipe 40. The molten metal may be introduced between the mold sections 14 and 22 respectively either before or after the introduction of the cooling medium to the respective compartments 12 and 36, and will be quickly cooled in the desired shape by the action of the cooling medium. Consequently the casting of the pipe sections is greatly expedited. Upon introduction into the compartment 12, the water or other cooling medium will pass directly onto the lower base of the mold member 14 thereby keeping this mold member cool at all times. During its passage through the compartment 12, it will be brought in contact with the mold member 14 thereby serving to cool this member as well as the base. It should be noted that the cooling medium passes about the ends of the mold member 22 so as to cool the same sufficiently at these points. 80

From the foregoing, it is believed that the advantages and novel features of my invention will be readily understood and, therefore, further detail description is deemed unnecessary. 85

In reducing my invention to practice, I find that the form referred to herein as the most practical and preferred embodiment is the most efficient, but realizing that certain conditions will necessarily vary in con- 90 currence with the adoption of my device, I desire to emphasize the fact that various minor changes in the details of construction and in the proportion of parts may be re- 95 sorted to when required without sacrificing any of the advantages of my invention as defined in the appended claim.

Having thus fully described my invention, what I claim as new and desire to secure by Letters Patent is:— 100

A mold, comprising hollow mold members, which are in communication and through which a cooling medium is adapted to be circulated, one of the mold members 105 having connecting portions extending across the space thereof and forming ties for the inner and outer walls, and having a pair of openings in each connecting portion, and a recess in the mold face in communication 110 with the pair of openings, a sliding cut off in each recess, and a lever in one opening of each pair of openings, and having the cut off connected thereto.

In testimony whereof I affix my signature 115 in presence of two witnesses.
